UNITED STATES PATENT OFFICE.

RICHARD M. CHUNN, OF CLARENDON, TEXAS.

MAP HANGER.

1,405,284.

Specification of Letters Patent. Patented Jan. 31, 1922.

Application filed September 5, 1919. Serial No. 321,941.

To all whom it may concern:

Be it known that RICHARD M. CHUNN, a citizen of the United States of America, residing at Clarendon, in the county of Donley 5 and State of Texas, has invented new and useful Improvements in Map Hangers, of which the following is a specification.

The object of the invention is to provide a map exhibiting hanger or holder for use 10 in supporting in position for ready reference a plurality of maps, particularly of the type in which the back of the map is utilized to carry data and explanations in the way of population, historical information, area, 15 boundaries and the like, which cannot conveniently be placed upon the face of the map, but without reference to which the value of the map is incomplete; and furthermore to provide a device for the purpose indicated which may be utilized under conditions 20 which will economize in the space occupied as compared with that which would be necessary if the maps were independently exposed for convenient inspection.

25 To this end the invention consists in a construction and combination of parts illustrated in the accompanying drawing, it being understood that changes in form and proportion may be resorted to without departing from the principles involved.

In the drawing:

Figure 1 is a perspective view of the holder showing a map supported in position for inspection.

35 Figure 2 is a view of the holder arranged to expose the reverse side of a map to permit of consulting the data on the back thereof.

Essentially the device consists of a supporting plate or board 10 which may be of 40 any suitable material and of any desired shape or size, suitably ornamented or decorated to render it attractive, upon which at an intermediate point is mounted a rectangular swinging frame 11 having side arms 12 connected at their front ends by a cross rod or roller 13 adapted to receive the supporting eyes 14 of a plurality of maps 45 15. Connected with the side arms of the frame are operating cords 16 provided with terminal hooks 18 which may be engaged with studs 17 to maintain the frame 11 in a horizontal position. Also connected with 50 said operating cords are the elements 19 of a pull-cord so that the frame may be readily 55

moved from one position to another by grasping the common grip or hand hold 20.

At an intermediate point the cross rod 13 is provided with an eye 21 for engagement with a hook 22 to support the frame in an 60 upright position as when the maps are not in use. When a map is to be consulted the frame may be released and permitted to drop to a horizontal position whereupon one or more of the maps at the front may be turned 65 over the cross rod to drop in rear of the stack of maps supported by said rod and thus expose the particular map desired, after which the frame may be returned to its normal or upright position. 70

If the rear of a map is to be consulted the frame may be dropped to a hanging position as indicated in Figure 2 and an eye 23 at the free end thereof engaged with the hook 22 so that the data thereon may be read 75 at the convenience of the operator.

From the above description it will be obvious that a large number of maps may be supported by a single apparatus and yet any one of them may readily be exposed to 80 permit of consulting the same without interference by others suspended from the common cross rod 13.

What is claimed is:

A device of the kind described consisting 85 of a base for disposition against a wall, a rectangular swinging frame including side arms connected at their front ends by a cross rod for supporting a plurality of flexible elements each provided at one end with 90 spaced eyes loosely engaging said rod and provided at the opposite end with an eye, a hook carried by the base at the upper end thereof, cords connected with the side arms of the frame and trained through guides 95 supported on the base and provided with terminal hooks, studs carried on the base for engagement by the terminal hooks to support the frame in horizontal position, and flexible elements having a common hand grip and connected with said cords, whereby the frame may be swung to elevate the cross rod to dispose the backs of elements toward the base, or lowered to permit the inversion 100 of the elements with their front faces toward the base and their eyes in engagement with the hook on said base. 105

In testimony whereof he affixes his signature,

RICHARD M. CHUNN.
